DESIGN FOR A SIGNAL FOR MOTOR VEHICLES

Paul Falke, Weehawken, N. J.

Application January 18, 1937, Serial No. 67,124

Term of patent 14 years

To all whom it may concern:

Be it known that I, Paul Falke, a citizen of the United States, being a resident of the city of Weehawken, in the county of Hudson and State of New Jersey, have invented a certain new, original, and ornamental Design for Signals for Motor Vehicles, of which the following is a specification, reference being had to the accompanying drawing, which forms a part thereof.

The figure is a perspective view of a signal for motor vehicles showing my new design.

I claim:

The ornamental design for a signal for motor vehicles, as shown.

PAUL FALKE.
